UNITED STATES PATENT OFFICE

MICHAEL GILSON, OF FREDONIA, WISCONSIN

CONCRETE MIXER

Application filed January 20, 1930. Serial No. 422,075.

This invention relates to improvements in concrete mixers.

One of the objects of my invention is the provision of improved locking means for concrete mixers, wherein the mixing drum can be quickly and easily locked either in a charging or discharging position and when moved to a charging position will be locked against movement until released by the operator.

Another object of my invention is the provision of a locking device for the mixing drums of concrete mixers, wherein means is provided for direct engagement with the operating shaft that raises the drum to discharging position whereby to hold the drum in discharging position until released by the operator, such means being moved to an operative position whereby to automatically lock the drum when it is returned to its normal or charging position.

A further object of the invention is the provision of locking mechanism of the above character which includes a hand lever normally positioned in a substantially vertical plane and provided with a notch portion adapted to be engaged by a pivoted arm carried by the drum shaft for maintaining the drum against movement while in charged position and adapted to be released from the lever to move the drum to discharging position whereby, the lever can be moved upon its pivot for engaging the locking pin carried thereby with the locking gear carried by the drive shaft which rocks the drum.

With the above and other objects in view, the invention consists in the novel features of construction, the combination and arrangement of parts hereinafter more fully set forth, pointed out in the claims and shown in the accompanying drawings wherein:

Figure 1 is an end elevation looking at the operating mechanism for tilting the drum to discharging position with the locking mechanism in position for locking the drum in discharging position;

Figure 2 is a similar view with parts broken away illustrating the parts in position for locking the drum in charging position;

Figure 3 is a detailed side elevation with

parts thereof broken away and illustrated in cross section.

The present invention is applicable to various types of portable concrete mixers wherein in the drum 1 is rotatably mounted upon a suitable frame 2 and in the present instance, I have illustrated only a small portion of the drum 1, mounted upon the supporting frame through the medium of the bearing 3.

The drum 1 is moved to discharging position through the medium of the internal gear 4 which carries therewith the bearing plate 5, having a serrated flange 6 and mounted upon the end of the shaft 7 is an arm 8, the end of which is provided with a serrated face 9 cooperating with the serrated face on the flange 6 for retaining this arm in various adjusted positions relative to the gear 4.

Supported upon the frame 2 is a bracket 10 and extending upwardly from the upper face of the bracket are the spaced bearing standards 11, supporting the shaft 12 to the outer end of which is attached the hand wheel 13 which is keyed to the shaft 12 and used for rotating this shaft. The wheel 13 has attached to its rim the handle 14 for manually rotating the wheel.

Upon the inner end of the shaft 12 is a pinion 15 cooperating with internal gear 4 to impart a tilting movement to the drum 1. Extending laterally from the bearing standards 11 are the spaced arms 16 which support the pin 17, upon which locking lever 18 is mounted.

Lever 18 carries a laterally projecting pin 19, which is adapted to engage within any one of the recesses 20 formed in the perimeter of disc 21 when the drum is in discharging position, as shown in Figure 1, for retaining the drum against further movement and as arm 8 is rotatable with the internal gear 4, this arm will assume an upwardly projecting position, as shown at Figure 1. However, when lever 18 is moved to the position for locking the drum in discharging position, this lever will assume a vertical position, as shown in Figure 2.

The inner end of lever 18 is provided with a shouldered part 22 forming substantially angular faces, and within this shouldered

part, the outer end of arm 8 is adapted to be engaged, as shown in Figure 2, for locking the drum in charging position.

When the lever 18 is moved from a position locking the drum in discharging position to a normally unlocking position, this lever is supported in a vertical position by engaging the upper face 23 of bracket 10, then the notched portion 22 will be in position to receive the outer end of arm 8, the engagement of arm 8 moving lever 18 to a horizontal position, as shown in Figure 2, and locking the drum in discharging position.

It will be apparent from the foregoing that I have provided a comparatively simple and inexpensive device adapted to be applied to concrete mixers of various types, particularly that type wherein the mixing drum is manually moved from a charging to a discharging position, and wherein the drum is counter-balanced so that when it is unlocked from a discharging position, the counter-balancing of the drum will return the drum toward an operating position, moving arm 8 into engagement with the inner end of lever 18 and locking the parts, as illustrated in Figure 2, so that the drum will be securely held in a charging position. The construction of the device is such that it can be easily installed and comprises a very few number of parts so as to reduce the manufacturing cost, and its operation is not only simple, but positive.

While I have shown and described the preferred embodiment of my invention, it will be apparent that slight changes may be made in the construction when putting the invention into practice without departing from the spirit of the same or the scope of the appended claims.

I claim:

1. In a device of the class described and in combination a support, a movable member on the support, a shaft operatively connected with the drum, operating mechanism having connection with the shaft for imparting movement thereto, a pivoted lever upon the support, means for operatively connecting the lever with the operating mechanism for retaining the drum in a discharging position, said lever having a shouldered portion at one end and an arm carried by the shaft and adapted to have one end engaged with said shouldered portion for locking the drum in a charging position.

2. A concrete mixer including a support, a movable member on the support, a shaft operatively connected with the drum, operating mechanism having connection with the shaft for imparting movement thereto, including a rotatable disc having spaced recesses circumferentially thereof, a pivoted lever on the support, a lateral pin carried by the lever and adapted to be moved into any

one of the recesses in the disc for retaining the drum in a discharging position, an arm movable with the drum, and a shouldered portion on the lever adapted to be engaged by the outer end of said arm for locking the drum in an operating position.

In testimony that I claim the foregoing I have hereunto set my hand at Fredonia, in the county of Ozaukee, and State of Wisconsin.

MICHAEL GILSON.
